(57) **CLAIM**

The ornamental design for a torpedo level, as shown and described.

DESCRIPTION

FIG. 1 is an isometric view illustrating a torpedo level incorporating our new design, wherein areas illustrated in phantom form no part of the claimed design;
FIG. 2 is an elevation view of one side thereof;
FIG. 3 is a top plan view thereof;
FIG. 4 is an elevation view of the opposite side thereof;
FIG. 5 is a bottom plan view thereof; and,
FIG. 6 is an end elevation view thereof.
